UNITED STATES PATENT OFFICE.

DANIEL W. O'BRIEN, OF ST. PAUL, MINNESOTA.

GAME APPARATUS.

1,370,148.

Specification of Letters Patent. Patented Mar. 1, 1921.

Application filed June 5, 1920. Serial No. 386,696.

To all whom it may concern:

Be it known that I, DANIEL W. O'BRIEN, a citizen of the United States, residing at St. Paul, in the county of Ramsey and State of Minnesota, have invented certain new and useful Improvements in Game Apparatus, of which the following is a specification, reference being had to the accompanying drawings.

10 This invention relates to games, and particularly to games in which a board is used having a spinner or arrow adapted to be spun by a player, the board being provided with a circular series of spaces, marks or 15 other indications, and the game progressing in accordance with the position of the arrow with relation to said marks, indications or spaces after the arrow comes to rest.

One of the objects of my invention is to 20 provide a board so marked and provided with such a spinner that a similitude of the game of baseball may be played on one side of the board, while a similitude of the 25 game of football may be played upon the other side.

A further object is to provide a baseball 30 game in which the spinner, when struck, moves over the series of spaces, these spaces being marked to indicate balls, strikes, outs, 35 base hits, home runs, and the like incidents of baseball playing, and on which provision is made for counting strikes, the number of 40 players who are out, and the number of balls delivered.

45 A further object is to provide a board for playing a similitude of football and having a spinner which, when struck, will move around a series of spaces concentric to the center of the spinner, these series of 50 spaces being designed to indicate complete and incomplete plays, the gains or losses, there being also a series of spaces concentric to the center of the spinner for indicating the distance of punts, kick-offs, and the like, 55 the board being further laid out to represent a football field divided by a transverse line into field spaces with goals at the opposite ends of the field, and the rules being such that the spinner will indicate by 60 its stopping at any particular space an event in the game of football.

Other objects will appear in the course of the following description.

My invention is illustrated in the accompanying drawings, wherein:

55 Figure 1 is a face view of one face of my game board as arranged for playing "baseball";

Fig. 2 is a side elevation of the pointer used;

Fig. 3 is a perspective view of one of the playing pieces;

Fig. 4 is a fragmentary cross sectional view of the board X;

Fig. 5 is a face view of the other side 65 of the board as designed for playing "football";

Fig. 6 is a view of a playing piece of "ball";

Fig. 7 is a perspective view of the "yard- 70 stick" used for measuring gains or losses made by players.

Referring particularly to the drawings, and particularly to Fig. 1, which illustrates the baseball game before referred to, X 75 designates the board, which is preferably divided in the middle so that it may be folded up, one side of this board having thereon the diagrams, marks, indicia, etc., for playing a game of baseball, and the other side 80 of the board being provided with diagrams, marks, indicia, etc., for playing a game of football. That side of the board X, which I have marked A and which is designed for playing baseball, is provided with a circular series of spaces. These spaces 10 may be of the same extent or certain spaces may 85 be shorter or longer than certain other spaces. I have indicated these spaces as all being of the same extent, and I have shown 90 32 of these spaces. Of these 32 spaces, I have shown 8 of these spaces as marked with the word "Out", 6 of these spaces as marked with the word "Strike", 8 of these spaces are marked with the word "Ball", 6 95 of these spaces as marked with the words "Base hit", and 2 of the spaces as marked with the words "Home run." Of the 6 spaces marked "Base hit", 2 of the spaces are marked "1 base hit", 2 of the spaces are 100 marked "2 base hit" and 2 of the spaces are marked "3 base hit". The several "out", "strike", "ball", "base hit", and "home run" spaces may be arranged in any suitable order, but I have so arranged them that 105 no two of the same character will come to-

gether. Thus, for instance, one of the "2 base hit" spaces is diametrically opposite one of the "3 base hit" spaces and the other "3 base hit" space is diametrically opposite 5 a "1 base hit" space, so that the spaces will read, for example, consecutively, "Base hit", "Strike", "Out", "Ball", "Base hit", etc.

Within the circle of spaces 10 are disposed indications of the home plate and 10 the first, second and third bases arranged as usual on a baseball diamond. Four pieces 11 are provided as markers and represent men, and are disposed on the base squares 12 or at the home plate 13 as the game progresses. A spinner is provided in the form 15 of an arrow 14, which is preferably provided with a central hub whereby it may be raised off the board slightly and provided with a central pin 15 passing through 20 the center of the board. At the upper portion of the board are provided spaces 16 for keeping the score throughout the 10 or 11 innings through which the game may run, and score markers having suitable 25 numbers, indicating runs on them, are to be placed in these squares, or the score may be written within these squares.

On the corners of the two sections of the board are raised portions 17 to prevent the 30 face of the board from being marked or rubbed. For the purpose of indicating the number of balls pitched, the board is marked off with a square 18 having thereon the word "Balls 1, 2, 3, 4" and an arrow 19 is pivoted 35 upon the board so as to be shifted to any one of these numbers. A like square 20 is marked on the board having therein the word "Strikes" with the numbers 1, 2, 3, and an arrow 21 is used to score these strikes. 40 Between the squares 18 and 20 there is a rectangular space 22 marked with the word "Out" and the numerals 1, 2, 3, and an arrow 23 coacts with these numerals so as to indicate the number of men out.

45 The game is played by two persons, each one representing a team. The game is played by the same rules as a game of baseball, except that the arrow or indicator 14 is spun instead of there being actual batting. 50 To start the game, one of the players spins the arrow, and where it stops on one of the spaces 10 indicates the play. For example, if the arrow stops on "Strike," it means that one strike is to be counted and marked in 55 the strike space 20, and so on. If on the next turn or spin of the arrow 14, it stops on the words "2 base hit," one of the markers 11 is placed on the second base, that is the space 12 indicating second base, and the little arrow 20 is turned back from "Strike" on 60 the marker. The same person spins the arrow each time until three outs have been counted against him in the space 22 and then the other team, represented by the other 65 player, takes its turn, and so on until each

team or player has played as many innings as has been decided on for a game. Of course, it will be understood that four balls puts a man on first base, that is "walks" the man to first base. Three strikes are out, and if the arrow stops on the dividing line between the different plays, it is a foul ball. The first two fouls are to be considered strikes.

On the face B of the board there is shown 75 a representation of a football field. To this end, the actual field of play is marked off by longitudinally extending, parallel lines 24 and a goal 25 is marked off at each end of the field. The field is divided by transverse 80 lines 26 at every five yards and the side lines 24 have fractional indications 27, each of these indications indicating a yard. The middle line 28 of the field is 50 yards from each goal, and each of the five yard lines from 85 this middle line toward the goal is designated by its proper number, as by 45, 40, 35, etc. On the 50-yard line there is formed the recess "a" for the stub or spindle of the arrow before referred to, and concentric to 90 this center there is described a circular series of spaces 29. These spaces are shown as of equal length, and I have illustrated the board as being divided into 24 spaces concentric to the center. These spaces are 95 marked with words or indicia indicating gains or losses in yards. Thus, for instance, one of the spaces will have thereon the words "4 yards loss," the next "2 yards gain," the next "10 yards loss," the next "5 yards gain," etc. Three adjacent spaces 29 will be marked with the word "Incomplete" 100 and each set of spaces 29 marked "Incomplete" are separated from the like spaces by a space marked "Complete." The word "Complete" is applied only to those spaces where at least 10 yards are indicated as a gain, the rules of the game of football requiring that a player must gain 10 yards in 105 four "downs" or lose the ball. Therefore, if the pointer stops on any of those spaces designated "Complete," the player has gained at least 10 yards so that there is no question of the gain having been made in 110 four downs, that is there is no question of loss of the ball. The spaces 29 are separated from each other by radial lines 30, which also play a part in the game, as will appear later.

Extending from one of these radial lines 120 to another of these radial lines are a plurality of chordal lines 31 which are of equal length. There are 8 of these lines 31 and the spaces defined by these lines have their numerals and words indicating the distance 125 traversed by a ball on kick-offs and punts. Thus, for instance, two of these lines 31 have associated therewith the words "20 yards," two other spaces have the words "50 yards," two others "40 yards," etc. Asso- 130

ciated with each of the spaces 29 are relatively short, distinctive, circumferentially extending lines designated 32. These are for drop kicks, and in playing the game are 5 to be considered with the line 31, with which any particular line 32 is associated.

On one corner of the board a space 33 is left for the numerals 1, 2, 3, 4 and the word "Downs," and an arrow 34 is mounted at 10 this place so that it may be moved to indicate any one of the numerals. There are two of these spaces 33 and two of the arrows 34 disposed at diagonally opposite portions of the board for the two players. A playing piece 35 is used in the form of a football having an indicating point 36 at one end for convenience in disposing the ball on the proper line, and also used in connection with 15 the game is a yard stick or measure 37 divided by graduations into yard lengths.

The game is played by two persons and 20 may be played in quarters or halves, as desired. The players are supposed to be the captains of the rival teams and each must 25 name his play before the arrow 14 is spun. The player can use straight football, forward passes, punts, or if near enough can try for a field goal. Each of the spaces 29 is marked off for straight football and 30 forward passes. The 8 lines 31 are marked for kick-offs and punts, and if the indicator stops on one of the lines 30 separating the spaces when kicking, the kick is supposed to be blocked and the player loses the ball.

35 The lines 32 which are associated with each space 29 are used when "drop kicks" are made or when kicking goal after "touch downs." Each player has to gain 10 yards in four downs or lose the ball.

40 In order to start to play, the "ball" 35 is placed on one of the 45-yard lines and is supposed to be moved toward the adversary's goal. The arrow 14 is then spun, and if the arrow stops, for instance, on the 45 line 31 marked "40 yards," the ball is supposed to have been kicked 40 yards and, of course, gone into the hands of the other player. Therefore, the other player places the "ball" 35 on his own 15-yard line. He 50 then spins the arrow, previously stating his play, and has four downs (that is four spins of the arrow) in order to make 10 yards. If a player finds himself too near his own goal, he can kick or punt out of danger on 55 the first down. A touch-down is made by playing the ball over the opponent's goal line and counts 6 points, after which the player spins the arrow again and if it stops on one of the heavy lines 32, it counts 1

60 more point. A drop kick is made by spinning the arrow and having it stop on one of the lines 32, and consideration is to be taken of the yard line from which one is kicking. For example, if the player is kicking 65 from the 35-yard line, the arrow would

have to stop in a 40 or 50-yard space and also on the line 32 in order to make this drop kick count. If the arrow should stop on the 20 or 30-yard line, assuming that the player is kicking from a 35-yard line, the 70 opponent will start the ball from there.

In this game, a touch down counts 6 points, a goal after a touch down 1 point, a drop kick or field kick 3 points, and a touch back counts 2 points. If the arrow stops on 75 one of the radial lines 30, the player is penalized 5 to 15 yards, as may be decided on. A touch back is made by a player losing enough yards to put him back over his own goal line and counts two points for the 80 opponent. If a punted ball goes over the goal line, it is to be brought out to the 20-yard line and put again into play.

It will be understood that while I have referred to the arrows 34 as if they were 85 separate arrows from the arrows 19, 20 and 23, that as a matter of fact the same arrows will be used, each arrow being simply formed with a stem for insertion in an appropriate hole made in the board, though, 90 of course, separate arrows can be used. The same is true of the spinning arrow 14 which is designed to be used with one or the other of the two boards.

While I have stated and illustrated a particular arrangement of spaces and particular marking of the spaces in both of these games, it will be understood that the particular arrangement of the spaces and the marking of spaces might be varied in many 100 ways without departing from the spirit of the invention.

The yard stick shown in Fig. 7 is merely for convenience in measuring the losses or gains made by the ball 35, this ball being 105 provided with a pointer 36 at one end whereby its position may be accurately indicated.

I claim:—

1. A game apparatus comprising a game 110 board having on each of the opposite faces thereof a portion concentric to the center of the board and divided by lines into spaces extending in a circle around the board having indicia indicating different game values, 115 and a spinner pointer rotatably engageable with the center of either face of the board.

2. A game apparatus comprising a game 120 board having on the opposite faces thereof a portion concentric to the center of the board and divided by lines into spaces extending in a circular series around the center of the board, the spaces having indicia therein indicating different game values, and a spinner pointer rotatably engageable with the center of either face of the board, each face of the board having game scoring spaces provided with indicia thereon, and pointers rotatably engaging with either face 125 130

of the board and coating with the scoring spaces.

3. A game apparatus comprising a board having thereon the representation of a football field, the field being defined by parallel, longitudinally extending lines, these lines being graduated from the middle of the field in opposite directions to indicate yard lines and the spaces between said lines 10 being traversed by transverse yard lines, the board having upon its face a circular series of spaces concentric to the center of the board and divided from each other by radial lines, said spaces having therein indicia designating various football plays, a spinning pointer engageable with the center of the board and when spun moving over said circular series of spaces, and a playing piece movable over said field in accordance 15 with the indications of said pointer.
4. A game apparatus comprising a board having thereon the representation of a football field, the field being defined by parallel, longitudinally extending lines, these 20 lines being graduated from the middle of the field in opposite directions to indicate yard lines and the spaces between said lines being traversed by transverse yard lines, the board having upon its face a circular 25 series of spaces concentric to the center of the board and divided from each other by radial lines, said spaces having therein indicia designating yards gained or lost, there 30 being a second series of spaces disposed approximately concentric to the center of the 35

board and having therein indicia indicating yards secured in kicking or punting the ball, a spinning pointer engageable with the center of the board and when spun moving over said circular series of spaces, and 40 a playing piece movable over said field in accordance with the indications of said pointer.

5. A game apparatus comprising a board having thereon the representation of a football field, the field being defined by parallel, longitudinally extending lines, these lines being graduated from the middle of the field in opposite directions to indicate yard lines and the spaces between said lines 45 being traversed by transverse yard lines, the board having upon its face a circular series of spaces concentric to the center of the board and divided from each other by radial lines, the first named spaces having 50 adjacent thereto at the middle of each space a line indicating a relatively small space extending approximately concentric to the center of the board for the purpose of indicating successful drop-kicks and goal 55 kicking, a spinning pointer engageable with the center of the board and when spun moving over said circular series of spaces, and a playing piece movable over said field in accordance with the indications of said 60 pointer.

In testimony whereof I hereunto affix my signature.

DANIEL W. O'BRIEN.
